UNITED STATES PATENT OFFICE.

CHARLES HAMMELMANN, OF BUFFALO, NEW YORK.

PORTABLE FORGE.

SPECIFICATION forming part of Letters Patent No. 410,161, dated September 3, 1889.

Application filed December 18, 1888. Serial No. 293,939. (No model.)

To all whom it may concern:

Be it known that I, CHARLES HAMMELMANN, a citizen of the United States, and a resident of Buffalo, in the county of Erie and State of New York, have invented new and useful Improvements in Portable Forges, of which the following is a specification.

This invention relates more especially to that class of portable forges which consists, essentially, of an upright bellows, a hearth arranged above the bellows having a tuyere, and a casing inclosing these parts.

In compressing the bellows of a forge the air is expelled or exhausted from the upper chamber thereof by the compression of the lower chamber, and upon expanding this lower chamber to again fill it with air a suction is created in the upper chamber and the passage leading from said chamber to the tuyere which tends to draw the gases from the hearth into the bellows, and frequently results in the destruction of the bellows by the explosion of the gas confined therein.

The object of my invention is to overcome this objection by providing means whereby the gas is effectually prevented from being drawn into the bellows; also, to construct the tuyere in such manner that the blast will be utilized for cleaning the tuyere, so as to avoid clogging thereof, and, finally, to simplify the connections forming the passage between the bellows and the tuyere.

In the accompanying drawings, Figure 1 is a sectional elevation of a portable forge provided with my improvements. Fig. 2 is a horizontal section thereof, taken above the tuyere. Fig. 3 is a horizontal section of the tuyere and the casing connected therewith containing the check-valve. Fig. 4 is a vertical cross-section in line xx , Fig. 1, on an enlarged scale.

Like letters of reference refer to like parts in the several figures.

A represents the upright cylindrical casing inclosing the parts of the forge.

B is the upright bellows arranged within the casing A, and having movable top and bottom plates b b' and a central stationary plate or partition b^2 , which is secured to the casing A, as shown. The central and bottom plates b b' are provided with air-openings c , which are closed by upwardly-swinging clap-valves c' in the usual manner.

D is the hand-lever whereby the bellows is operated, and which is connected with the latter by a rod d , having a horizontal foot or bent portion d' , which is secured to the under side of the bottom plate b' of the bellows, the bent portion of the rod passing through an upright slot d^2 , formed in the side of the casing A.

E is the hearth or fire-pan secured within the upper portion of the casing A, above the bellows; and F is the tuyere arranged centrally upon the hearth and connected with the upper compartment of the bellows by a blast-pipe G, which consists of an upright section g and two horizontal sections g' g^2 .

h is a horizontal valve-casing arranged on one side of the tuyere F, communicating at its inner portion with the latter by a passage h' and connected at its outer end to the horizontal section g' of the blast-pipe, the outer end of the valve-casing being provided with an internal screw-thread, with which the external thread of the section g' engages.

i represents a spherical check-valve arranged within the casing h and adapted to close against the adjacent end of the section g' of the blast-pipe. The check-valve i rests in an inclined groove or way i' , which slopes toward the end of the pipe-section g' , so that the valve will tend to move against the end of said pipe by gravity. The movement of the check-valve is limited in one direction by the end of the pipe g' and in the other direction by stop-pins i^2 , formed inside of the valve-casing. Upon forcing a blast of air through the blast-pipe G the check-valve i is moved away from the end of the pipe g' and permits the blast to pass onward to and through the tuyere; but as soon as the blast ceases the valve rolls down the incline i' against the open end of the pipe g' and closes the latter, thereby preventing the suction which is created within the bellows during the period that the hand-lever is held in a depressed position from drawing the gases from the hearth and tuyere back into the bellows through the blast-pipe and endangering the safety of the bellows.

The valve-casing i is preferably made considerably larger than the pipe g' , so as to afford a wide and ample passage for the blast around the check-valve. The lower horizontal section g^2 of the blast-

pipe passes through an opening formed in the leather or flexible portion of the bellows, and is secured at its inner portion to the upper side of the partition-plate b^2 by a metallic strap j , the pipe being secured to the bow of said strap by a rivet or otherwise, so as to be held against turning. A block of wood k is fitted over the strap j and the inner portion of the pipe g^2 , and is secured to the upper side 5 of the partition-plate b^2 . This block forms a support to which the flexible portion of the bellows surrounding the opening through which the pipe g' passes may be tacked, so as to form a reliable air-tight joint around 10 said pipe, and which would not be possible in the absence of the block k .

The lower horizontal pipe-section g^2 is connected to the lower end of the upright section g , preferably by a T l , the lower end of 20 which is closed by a screw-plug l' , so that any ashes or sediment accumulating therein may be removed. The upper horizontal pipe-section g' is connected with the upper end of the upright section g by an elbow m . The 25 upright section g is provided at its upper end with a movable screw thimble or nipple m' , which is provided with an internal screw-thread engaging with an external thread on the pipe and with an external thread engag- 30 ing with an internal thread formed in the adjacent portion of the elbow m .

In assembling the parts the upper and lower horizontal sections g' g^2 are first attached to the valve-casing i and the partition-plate b^2 , 35 and the T l and elbow m are screwed upon the outer ends of said pipes. The upright section g , which is made somewhat shorter than the distance between the elbow and T , is then screwed to the latter, and the thimble, 40 which has been previously screwed down upon the pipe g to admit it between the T and elbow, is now screwed upward on the pipe g and with its upper end into the elbow. This forms a very simple construction, which permits the 45 parts of the blast-pipe to be readily connected and disconnected for cleaning the same or for other purposes.

The tuyere F consists of a hollow annular shell or casing, the lower part n of which is 50 preferably formed with the bottom plate of the hearth E , while the upper part n' thereof is bolted to said lower part. The upper part n' is provided with a central discharge-opening o and with a depending annular flange or 55 rim p , surrounding the opening o , and which projects downwardly a short distance into the shell of the tuyere, so as to compel the blast to dive under said flange before escaping through the opening o , and thereby keep clean 60 the interior of the tuyere and prevent accumulation of ashes in the same.

q is a cup-shaped receptacle arranged within the tuyere directly underneath the discharge-opening o and separated from the depending 65 flange p by a narrow space, forming a passage for the blast. The cup q catches any ashes falling through the discharge-opening o , and

as soon as they are deposited in the cup they are blown out by the blast. The cup q is provided at its upper edge, in front of the passage h' , with a guard or deflector r , which 70 prevents the blast from escaping directly through the discharge-opening o and compels the same to pass wholly around the cup before escaping, thereby causing the blast to 75 circulate through the entire inner portion of the tuyere and clearing all parts thereof. The cup q is provided on its under side with a stem s , which is seated in a socket in the lower plate n of the tuyere, and the cup is held 80 from rising out of place by upwardly-projecting pins t , formed on the upper side of the cup q and bearing against the under side of the top plate n' of the tuyere F .

The upper compartment of the bellows is 85 preferably compressed by means of spiral springs U , interposed between the under side of the hearth-plate and the top plate b of the bellows.

I claim as my invention—

1. In a forge, the combination, with a bellows and a tuyere or blast-discharge nozzle, of a blast pipe or passage connecting the bellows with said tuyere or discharge-nozzle, and a check-valve arranged in said passage, substantially as set forth. 90

2. In a forge, the combination, with a bellows and a tuyere, of a valve-casing connected with said tuyere and provided with an inclined way, a blast pipe or passage connecting said valve-casing with the bellows, and a check-valve arranged in the valve-casing upon said inclined way, substantially as set forth. 100

3. In a forge, the combination, with the tuyere and the bellows having a stationary partition b^2 , of a blast-pipe connecting the bellows with the tuyere and provided with a horizontal branch or section g^2 , entering an opening in the flexible portion of the bellows and secured to the partition b^2 , and a block 110 k , fitted over said pipe within the bellows and forming a support to which the flexible portion of the bellows surrounding the pipe is tacked, substantially as set forth. 105

4. In a forge, the combination, with the bellows and the tuyere, of the valve-casing h and check-valve i , the blast-pipe G , connecting the bellows with said valve-casing and composed of horizontal sections g' g^2 , and an upright section g , a T l , connecting the lower 120 horizontal section g^2 with the lower end of the upright section g , an elbow m , attached to the outer end of the upper horizontal section g' , and a movable screw thimble or nipple m' , attached to the upper end of the upright section g and connecting the latter with the elbow m , substantially as set forth. 125

5. In a tuyere for forges, the combination, with an annular shell or casing provided in its top with a discharge-opening and in its side with an inlet-opening, of a depending flange or rim surrounding said opening, a cup or receptacle arranged within the annular casing underneath said discharge-opening 130

- and depending flange, and a guard or shield arranged on said cup in front of the inlet-opening of the tuyere, substantially as set forth.
- 5 6. In a forge, the combination, with the hearth-plate or fire-pan, of a tuyere composed of a lower part n , formed in said hearth-plate and provided with a socket, an upper part n' , provided with a discharge-opening o and 10 a depending flange p , and a cup or receptacle q , arranged within the tuyere-casing underneath the discharge-opening o and provided with a stem seated in the socket of the lower part n of the tuyere, substantially as set forth.

Witness my hand this 12th day of December, 1888.

CHARLES HAMMELMANN.
